TELEPHONE ASSEMBLY

Blanche H. Kate, Minneapolis, Minn.

Application February 26, 1940, Serial No. 320,907

4 Claims. (Cl. 179—149)

This invention relates to a new and novel telephone assembly and more particularly to one in which the elements are all supported by a single base.

It has long been recognized in the telephone art that the necessity with present telephone assemblies of employing one or both hands for holding elements of the apparatus during a telephone conversation is a serious disadvantage. The hands obviously are not necessary to the actual process of voice transmission and there should be no need of employing the hands for the purely mechanical function of holding a receiver unit or receiver-transmitter unit. It is frequently desirable and even imperative that acts requiring the use of both hands be performed at the same time as the telephone conversation. Thus it is often necessary to make notes or to consult records during the conversation.

The principal reason why the existing telephone assemblies have been designed with this disadvantage is that the receiver and transmitter during the conversation must be close to the ear and mouth, respectively, and that no satisfactory arrangement has previously been devised for adjustably supporting the receiver and transmitter in the proper positions relative to the user regardless of his height and of the position taken by him during the conversation. With the earlier type of telephone in which the receiver and transmitter were embodied in separate units, it was often necessary to employ both hands, one to hold each unit. The so-called "French" type of telephone freed one of the two hands by combining the transmitter and receiver in one unit. Largely because of this, this type of telephone has become extremely popular and is now widely used to the almost total exclusion of the earlier types. But even with the "French" type of telephone, it is still necessary for one hand to be employed for the purpose of holding the receiver-transmitter unit.

It is a broad object of the present invention to provide a unitary telephone assembly wherein the receiver and transmitter are supported in such a manner as to free both hands of the user. While attempts have been made in the past to support either the receiver or transmitter or both, the resulting arrangements have all failed in one manner or another to provide for the convenient and simultaneous adjustment of both the receiver and transmitter. Thus in some cases, the receiver and transmitter have been associated with independent supports so that the

telephone user must separately adjust each unit for the position he is then occupying. Another arrangement provides for the mounting of a receiver-transmitter unit on an adjustable support. The provision for adjustment, however, is not such that the adjustment can be quickly made. Moreover, the support is fixed so that the degree of adjustment is relatively limited. In no one of these prior art arrangements is there a unitary telephone assemblage which can be readily moved about. With every one of these prior art devices, the user is so restricted in the use of the telephone that it would be more desirable to use the conventional telephone assembly in spite of its disadvantages.

The present invention has as an object to provide a unitary portable telephone assembly embodying means for supporting the receiver and transmitter in a conveniently adjustable manner.

A further object of the present invention is to provide such an assembly in which the receiver and transmitter are embodied in a single unit supported by a flexible member.

A still further object is to provide such a telephone assembly in which the flexible supporting member is in the form of a flexible conduit enclosing the conductors extending to the receiver and transmitter.

A still further object is to provide such telephone assembly in which means is provided for permitting a limited amount of swivel movement between the receiver transmitter unit and the flexible conduit.

A still further object is to provide a unitary telephone assembly of an improved type in which a manually operated switch is provided for making the circuit changes necessary to the operation of the telephone and in which a signal light is provided to remind the user to close the switch at the termination of a conversation.

A still further object of the invention is to provide a unitary telephone assembly such as set forth in the preceding objects in which it is impossible to adjust the receiver and transmitter to a position in which the assembly is unstable. Other objects and advantages will be apparent from the following description and the appended drawings in which

Figure 1 is a perspective view of the entire assembly;

Figure 2 is a diagrammatic scheme of the wiring system employed;

Figure 3 is a vertical section taken on the line 3—3 of Figure 1; and

Figure 4 is a horizontal section taken on the line 4-4 of Figure 3.

Referring in detail to the drawings, the telephone assembly of the present invention comprises a base 10, a transmitter and receiver unit 11, and a flexible supporting member 12. These three elements are permanently fastened together to form a single unitary structure.

The base member 10 is preferably molded of the phenolic condensation product commonly known as "Bakelite" or of some other suitable plastic molding material. The base member is in the form of a housing enclosing the usual switching mechanism, condensers, terminal panels, and the other apparatus usually located in such base members in telephone assemblies of the conventional type. The invention also contemplates that this base member may enclose a bell as is commonly done in recent telephone assemblies. Disposed on a forward portion of the base member is a dial 13 of conventional construction. Molded integrally with the base 10 is a hood 14 suitably curved to direct the light of an electric bulb contained therein upon the face of the dial 13. As will be pointed out later, this bulb is so wired in the telephone circuit that it is energized only when the circuit to the receiver-transmitter unit is closed. The bulb thus serves the dual purpose of illuminating the dial and of acting as a signal light to indicate a closed telephone circuit. Projecting from the lefthand side of the base member 10 is an operating handle 15 of a switch for controlling the circuits to the bell, the light, the receiver, the transmitter, and the other apparatus associated with the system.

In the illustrated form of the invention, a flange 17 projects downwardly from the front of the base member 10. This flange is designed to engage the edge of the desk or table upon which the telephone is disposed, and thus to prevent the telephone from sliding while dialing or adjusting the transmitter and receiver unit. While such a flange is highly desirable in those cases where the telephone is normally disposed close to the front edge of the supporting surface, it is desirably omitted where the telephone may be placed elsewhere on the supporting surface.

The transmitter and receiver unit 11 is of conventional form so far as the transmitter and receiver are concerned. The unit is essentially similar to the corresponding unit of the common "French" type of telephone assembly and comprises a transmitter portion 23 and a receiver portion 25 in a single molded casing. Like the base member 10, the transmitter and receiver unit is preferably molded of "Bakelite" or a similar material.

As previously noted, the flexible member 12 supports the transmitter and receiver unit 11 with respect to the base 10. As best shown in Figures 3 and 4, this member is in the form of a hollow conduit enclosing the conductor assembly 18 leading from the base member 10 to the transmitter and receiver unit. The member 12 is so formed that while the member is easily bent to any desired position, it will support the transmitter and receiver unit in that position until it is again manipulated. Any of numerous conventional types of flexible tubing having these properties may be employed for the present purpose.

The transmitter and receiver unit 11 is connected to the flexible tubing 12 by means of a swivel joint of limited movement, this joint being generally indicated by the reference numeral

19. This joint is shown in greater detail in Figures 3 and 4. It will be noted that the upper end of tubing 12 is provided with a portion 20 of reduced diameter projecting from the unit 12 and integral therewith, which is journaled in a hollow boss 21. The reduced portion 20 is provided with two slots 22 of substantially semi-circular form. These two slots are horizontally disposed and are separated by webs 24. Slidable within these slots 22 are two wedge-shaped guide pieces 26 which, in turn, are held in position by set screws 27. The set screws are threaded through the walls of boss 21 and are received in counter-sunk depressions in the guide pieces 26, in which depressions they are freely turnable. The set screws urge the wedge-shaped guide pieces 26 against the inside periphery of slots 22 to create a frictional connection between tube 12 and the boss 21. The set screws can be adjusted to maintain the desired amount of friction. It will be noted that the two members joined are firmly retained together as long as the set screws extend into the depressions in the guide pieces 26, but may be readily separated by slightly unscrewing the set screws. A very important feature of the joint 19 is that the swivel movement thereof is limited by the engagement of guide pieces 26 with the webs 24. This serves to limit the twisting of the conductor 18 as will be explained in more detail later.

By reason of the flexible tube 12 and the swivel connection 19, the receiver and transmitter can be quickly adjusted to a position which is comfortable for the user at the time the call is received. It is to be especially noted that because of the unitary nature of the assembly, the entire assembly can be readily moved so that the range of adjustment is not merely that provided by the tube 12. The swivel connection 19 further increases the adjustability of the support as is evident from the dotted line position of the parts in which the unit 11 has been rotated nearly 180° from the position shown in full lines. At the same time, it is assured that the conductors within the tube 12 cannot be damaged by excessive twisting. This is due to the provision of the webs 24.

The tube 12 is of such length that it is impossible to place the transmitter and receiver unit in a position in which the turning moment of the unit 11 about the nearest edge of base portion 10 is greater than the opposing moment exerted by the base member 10. Because of this relationship of the length of the tube 12 to the weights and configurations of the transmitter and receiver unit 11 and the base member 10, it is impossible at any time to place the transmitter and receiver unit in a position in which the telephone assembly is unstable. This greatly adds to the ease of adjustment since the user does not have to worry about where the transmitter and receiver unit is moved with respect to the base 10.

In the conventional type of telephone assembly wherein there are two separate units connected by a flexible cord, certain switching operations are carried out upon the removal of the receiver or the receiver and transmitter unit from its place of support on the base member. Inasmuch as the present invention eliminates this step, provision is made for manually performing this switching operation at the beginning and end of the conversation. As previously indicated, a switch operating handle 15 extends outwardly from the base member 10. The switch member actuated by this handle may take the form of a

conventional toggle switch. The switch not only controls various telephone circuits but also controls the energization of an incandescent bulb located in the reflector 14.

In order to understand better the function of the manual switch, the various circuit connections of the telephone assembly have been shown in Figure 2 in a highly schematic and a somewhat simplified form. Referring to this figure, a conventional bell ringing mechanism of the telephone is indicated by the reference numeral 30. A dialing mechanism is indicated by the numeral 31. The dialing mechanism is of any conventional form. Such dialing mechanism usually comprises a switch and means for periodically making and breaking this switch a predetermined number of times each time the dial is actuated, the number of times depending on the extent to which the dial is rotated. The making and breaking of this switch causes a series of current impulses at the telephone exchange to indicate the number being called. The numeral 32 indicates the incandescent bulb used in connection with the reflector 14. The switch actuated by operating handle 15 is designated by the reference numeral 34. This switch comprises a switch blade 35, movable between contacts 36 and 37. When the telephone is not being used, the switch blade 35 occupies the position shown in which it is in engagement with contact 36. When it is desired to use the telephone, the switch blade 35 is moved by manipulation of handle 15 into engagement with contact 37. The conductors connecting the telephone assembly with the exchange are indicated by the numerals 39 and 40.

With the switch 35 in the position shown, a circuit can be established to the bell ringing apparatus 30 as follows: from conductor 39 through switch blade 35, contact 36, conductor 41, bell ringing mechanism 30, and conductors 42 and 40.

When the user desires to use the telephone either to receive an incoming call or to make an outgoing call, he needs merely to flip the switch handle 15 so as to move switch blade 35 out of engagement with contact 36 and into engagement with contact 37. As soon as this is done, the bell ringing circuit is interrupted and a circuit is established to the transmitter and receiver, to the bulb 32, and to the dialing mechanism 31. The circuit to the transmitter and receiver unit 11 and the dialing mechanism 31 is as follows: from conductor 39 through switch blade 35, contact 37, conductors 44 and 45, the transmitter and receiver unit 11, conductors 46 and 47, the dialing mechanism 31, and conductors 48 and 49. The circuit to the bulb 32 is as follows: from conductor 39 through switch blade 35, contact 37, conductors 44 and 50, bulb 32, conductors 51 and 47, dialing mechanism 31, and conductor 48 to the conductor 49. It will be noted that the bulb 32 is connected in parallel with the transmitter and receiver unit 11. Where the transmitter and receiver are included in separate circuits as is often the case, the bulb 32 may be connected in parallel with either the transmitter or receiver, preferably the former. It is also to be understood that the bulb, if desired, may be connected in series with the transmitter or receiver. In general, the bulb may be connected any place in the circuit wherein its energization will be controlled by the switch 35 and wherein it will not interfere with the operation of the apparatus.

As previously indicated, the bulb 32 not only serves to illuminate the dial 13, but also to remind the user that the switch 15 is still in the

conversation position. By reason of this light, it will be assured that the switch will be returned to its normal position upon the termination of the conversation.

5 From the foregoing, it will be noted that the present telephone assembly is in the form of an extremely compact portable unit which provides for convenient and simultaneous adjustment of the transmitter and receiver throughout any desired range of adjustment. The entire assembly can be moved out of the way when the conversation is completed and quickly restored to a convenient talking position when it is again desired to use it. By the use of the assembly of the 10 present invention, the need for using the hands during the conversation is entirely eliminated. The hands are entirely free to perform any desired tasks.

It is to be understood that the invention herein disclosed is merely a preferred embodiment and may be varied and modified in detail without departing from the scope of the invention.

What is claimed is:

1. A portable unitary telephone assembly comprising a desk-type casing for telephone operating parts formed with a tube-supporting mounting at the top thereof, a hollow flexible tube secured at its inner end to said casing top mounting and having secured to its outer end a combination hand transmitter-receiver unit, the flexible tube being readily bendable for adjustment purposes but having sufficient rigidity to support the transmitter-receiver unit in any adjusted position, telephone circuit conductors extending from the casing to the transmitter-receiver unit through the flexible tube, and manual switch means in the casing for controlling said circuit.

2. A portable unitary telephone assembly comprising a desk-type casing for telephone operating parts, said casing having a projecting upper portion of smaller cross-section than the main portion of the casing forming a vertical pedestal, a hollow flexible tube secured at its inner end to the upper end of said pedestal and having secured to its outer end a combination hand transmitter-receiver unit, the flexible tube being readily bendable for adjustment purposes but having sufficient rigidity to support the transmitter-receiver unit in any adjusted position, telephone circuit conductors extending from the casing to the transmitter-receiver unit through the flexible tube, and manual switch means in the casing for controlling said circuit.

3. A portable unitary telephone assembly comprising a desk-type casing for telephone operating parts, said casing tapering in its upper portion to a relatively small top forming a tube-supporting mounting, a hollow flexible tube secured at its inner end to said top mounting and having secured to its outer end a combination hand transmitter-receiver unit, the flexible tube being readily bendable for adjustment purposes but having sufficient rigidity to support the transmitter-receiver unit in any adjusted position, telephone circuit conductors extending from the casing to the transmitter-receiver unit through the flexible tube, and manual switch means in the casing for controlling said circuit.

4. A portable unitary telephone assembly comprising a desk-type casing supporting telephone operating parts including an exposed telephone dialing unit, said casing having a projecting upper portion terminating in a relatively small top forming a tube-supporting mounting, a hollow flexible tube secured at its inner end to said top

mounting and having secured to its outer end a combination hand transmitter-receiver unit, the flexible tube being readily bendable for adjustment purposes but having sufficient rigidity to support the transmitter-receiver unit in any adjusted position, a hood formed in the side of the casing upper portion and housing an electric lamp for illuminating the dialing unit, telephone circuit conductors for energizing the transmitter-

receiver unit extending thereto from the casing through the flexible hollow tube and connecting with said lamp to supply illuminating current thereto, and a manually operable on and off switch in the casing operable independently of the adjusted position of the transmitter-receiver unit to simultaneously energize and deenergize the transmitter-receiver unit and the lamp.

BLANCHE H. KATE.
